UNITED STATES PATENT OFFICE

160,764

COMBINED COASTER AND BRACKET

Gorman L. Bender, Wichita, Kans.

Application May 14, 1949, Serial No. 2,649

Term of patent 14 years

(Cl. D44—10)

To all whom it may concern:

Be it known that I, Gorman L. Bender, a citizen of the United States, residing at Wichita, in the county of Sedgwick and State of Kansas, have invented a new, original, and ornamental Design for Combined Coaster and Bracket, of which the following is a specification, reference being had to the accompanying drawing, forming part thereof.

Fig. 1 is a perspective view of a combined coaster and bracket, showing my new design.

Fig. 2 is a plan view;

Fig. 3 is a side elevational view; and

Fig. 4 is a front elevational view thereof.

I claim:

The ornamental design for a combined coaster and bracket, as shown.

GORMAN L. BENDER.
